TIRE

Glen L. Wittenmyer, Akron, Ohio, assignor to The
B. F. Goodrich Company, New York, N.Y., a cor-
poration of New York

Filed Sept. 6, 1966, Ser. No. 3,739

Term of patent 14 years

(Cl. D90—20)

FIG. 1

FIG. 2

FIG. 3

FIG. 1 is a perspective view of a tire showing my new design.

FIG. 2 is an enlarged fragmentary plan view of a portion of the tread of the tire shown in FIG. 1; and

FIG. 3 is a fragmentary transverse sectional view through the tire substantially on the plane indicated by the line 3-3 of FIG. 2.

The dominant features of the design reside in those portions shown in full lines.

I claim:

The ornamental design for a tire, substantially as shown and described.
